UNITED STATES PATENT OFFICE.

STEPHEN A. DOUGLAS VOLK, OF MINNEAPOLIS, MINNESOTA.

DESIGN FOR A BUILDING-BLOCK TOY.

SPECIFICATION forming part of Design No. 18,592, dated September 4, 1888.

Application filed April 24, 1888. Serial No. 271,740. Term of patent 14 years.

To all whom it may concern:

Be it known that I, STEPHEN A. DOUGLAS VOLK, a citizen of the United States, and a resident of the city of Minneapolis, county of Hennepin, State of Minnesota, have invented a certain new and useful Design for Building-Block Toys, of which the following is a specification, reference being had to the accompanying drawing.

10 My design consists in a grotesque building-block toy representing a human figure blocked out in angles.

The single view in the drawing represents my design in perspective.

15 It will be noted that all the lines of the figure are straight lines. No rounded or curved lines are used in the delineation. In artists' technical language, the figure is "blocked out in angles."

20 On the head of the toy may be pictured a

laughing face, and on its body may be indicated wearing-apparel, as having a tendency to increase the resemblance to a person and to heighten the grotesque effect. In the drawing I have also shown, on the body of the toy, letters of the alphabet, composition, pictures of various animals, &c.; but it will be readily understood that these features are not of the essence of the invention. 25

What I claim, and desire to secure by Letters Patent of the United States, is as follows:

The design herein shown and described, consisting in a grotesque building-block toy representing a human figure blocked out in angles.

STEPHEN A. DOUGLAS VOLK.

In presence of—

JAS. F. WILLIAMSON,
EMMA F. ELMORE.
